W. A. REDMAN.
COUPLING CENTERING MECHANISM.
APPLICATION FILED SEPT. 23, 1916.

1,226,116.

Patented May 15, 1917.

UNITED STATES PATENT OFFICE.

WILLIAM A. REDMAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-CENTERING MECHANISM.

1,226,116.

Specification of Letters Patent.

Patented May 15, 1917.

Application filed September 23, 1916. Serial No. 121,780.

To all whom it may concern:

Be it known that I, WILLIAM A. REDMAN, a citizen of the United States, residing at Pittsburgh, in the county of Allegheny and State of Pennsylvania, have invented certain new and useful Improvements in Coupling-Centering Mechanism; and I do hereby declare the following to be a full, clear, and exact description of the invention, such as will enable others skilled in the art to which it appertains to make and use the same.

My invention relates to that class of car couplers which are mounted upon railway cars in a manner permitting them to move or swing laterally when the cars to which they are applied pass around curves in the track; and the object of the invention is to provide simple and efficient means whereby the trainman may readily unlock the coupler and shift it laterally to any position that may be necessary to bring it into proper coupling alignment with the mating coupler upon an adjacent car.

Generally stated, this object is accomplished by employing a jointed lever for unlocking the coupler and shifting it laterally, one section of the lever being rotatable with respect to the other to effect an unlocking movement of the coupler locking mechanism, and the lever as a whole being rotatable to effect a lateral shifting of the coupler.

In the drawings illustrating the preferred embodiment of the invention, the scope whereof is pointed out in the claims,

Figure 1 is a front elevation of a laterally movable coupler combined with coupler unlocking and shifting mechanism embodying my invention.

Fig. 2 is a detail view, partly in side elevation and partly in vertical section, showing portions of the mechanism illustrated in Fig. 1.

Fig. 3 is a detail side elevation of one of the jointed operating levers and associated parts.

Fig. 4 is a detail view, partly in elevation and partly in vertical central section, showing the preferred mode of attaching the lever to the railway car.

Fig. 5 is a detail vertical sectional view of the separable members forming the socket or support for the jointed operating lever.

Fig. 6 is a detail plan view of the lower one of the bracket members shown in Figs. 4 and 5.

Fig. 7 is a transverse vertical section of the parts illustrated in Fig. 5.

Fig. 8 is a detail view, partly in elevation and partly in vertical transverse section, showing the preferred manner of mounting the operating lever upon the car body.

As the invention is generally applicable to couplers designed to be capable of lateral or swinging movements with respect to the cars to which they are applied, it will be understood that the details of construction of the car coupler illustrated in the drawings are not essential features but merely represent preferred forms.

In the drawings, 1 indicates a coupler having a knuckle 2 and a vertically movable lock 3 for retaining the knuckle in closed or locked position. The illustrated form of coupler is of a well-known type that is adapted to shift or swing laterally in either direction from its normal position in the longitudinal axis of the car to which it is attached. The lock 3 of the coupler may be moved to unlocked position by means of a pivoted lifter or actuating member 4 whose outer end enters a slot or aperture in the lower end of the lock and whose inner end is fashioned with aligned pintles 5 which project laterally in opposite directions and rest in hook-like bearings 6 formed on a bracket 7 that is secured to the coupler so as to be movable therewith. At its rear end the lock-actuating member 4 is provided with a pocket or recess 8 which receives the upwardly extending inner ends 9 of rotatable rods or bars 10 that respectively extend from the coupler toward the opposite sides of the car. By rotating either of the rods 10 the coupler lock 3 may be caused to assume an unlocked position and, in case the coupler is provided with knuckle-opening mechanism, the knuckle 2 may be caused to rotate to open position. This lock-actuating mechanism, which is to be regarded as illustrative merely, is fully described in the I. H. Milliken Patent No. 1,184,116, issued May 23, 1916.

Since the same form of mechanism is employed for actuating both of the rods 10, only one such actuating mechanism has been illustrated, and while it is preferred to use two rods 10 with their actuating mechanisms, so that the operator while standing at either side of the car may unlock the coupler and shift it laterally in either direction, it is to be understood that a single rod 10 and the

actuating devices appurtenant thereto may alone be employed.

Each rod 10 is pivotally connected to an operating lever, such connection being preferably formed by providing the outer end 5 of the rod with jaws 11 which receive the operating lever between them, and by passing a bolt 12 through corresponding holes in the said jaws and lever. The operating lever is comprised of a plurality of pivotally connected members, 13 and 14, respectively, the rod or bar 10 being connected to the lower member or handle section 13. The pivotal connection between the sections 13 and 14 of the operating lever is such that the handle section 13 may be rotated independently of the upper section 14 in a direction to effect a rotation of the attached operating rod 10 and a consequent unlocking 10 movement of the coupler lock 3. For this purpose, therefore, the lower end of the lever member 14 is preferably formed with jaws 15 which overlap the upper end of the handle member 13, the jaws 15 and member 13 being suitably perforated to receive a 15 pivot bolt 16. While this form of joint between the sections 13 and 14 of the operating lever permits the handle section 13 to be independently rotated in the direction of 20 length of the car so as to act as a complete lever in itself, it also enables both sections 13 and 14 to act conjointly as a single lever when the operator pulls or pushes transversely upon the handle member 13 to communicate a corresponding lateral shifting to 25 the coupler through the rod 10.

At its upper end the section 14 of the operating lever is provided with a projection or ball 17 which fits into a socket device 40 that is secured to the car by means of bolts 18. This socket device is preferably formed as two separable cupped members, 19 and 20, respectively, the member 19 being slotted, as at 21, to permit the lever member 14 to 45 be assembled therewith, and the member 20 being provided with a depending tongue 22 adapted to project into and form a closure for the slot 21. The lower inner face of the tongue 22 is cut away somewhat at 23 (see 50 Fig. 8) in order to allow assembly of the parts. As will be seen from an inspection of Figs. 4, 5, 6 and 7, the opening in the member 19 through which the lever section 14 extends is formed with oppositely disposed 55 downwardly flaring recesses or slots 24 which afford clearance permitting the lever member 14 to execute the extended swinging or pivotal movements transversely of the car requisite to effect the lateral shifting 60 or positioning of the coupler. The construction is such that there is no substantial oscillation of the upper section 14 of the lever in the direction of length of the car. In order to prevent the socket members 19 and 20 from shifting laterally upon each

other, as well as for the purpose of economizing metal, the upper socket member 20 is preferably provided with a central projection 25 in which the ball-receiving hemispherical cup is formed, the lower member 70 19 being formed with a recess 26 corresponding to said projection.

The operation of the described mechanism is as follows: When the coupler is to be unlocked the trainman grasps the handle end 75 of the lower lever member 13 and pulls it forwardly in the direction of length of the car, thus causing it to rotate about the pivot bolt 16 by which it is connected to the upper section 14 of the lever. This effects a rotation of the adjacent rod 10 resulting in actuating the lock lifter 4 and moving the coupler lock 3 to unlocked position. If the knuckle is free to open and the coupler is provided with knuckle-opening mechanism, 80 as is usually the case, this movement of the lever member 13 also causes the knuckle 2 of the coupler to be rotated to open position. When the coupler has been unlocked or the knuckle thereof thrown open, the lever member 13 and adjacent rod 10 may be returned to normal positions, the recess or pocket 8 in the rear of the lifter 4 being sufficiently wide to permit the rod 10 to resume its normal position while the locking mechanism 95 of the coupler remains in unlocked position. When the coupler is to be shifted laterally the operator moves the handle member 13 of the lever in a direction transversely of the car, pulling or pushing upon it as the 100 required direction of movement of the coupler may dictate. In this operation the lever sections 13 and 14 function as a single rigid lever rotating about the upper end of the section 14. By this means the attached rod 10 is shifted transversely and the coupler is correspondingly shifted. The operation of shifting the coupler laterally may be performed either when the coupler is locked or 105 unlocked.

I claim:

1. In mechanism of the character indicated, the combination with a laterally movable car coupler, of means for moving the locking mechanism of said coupler to unlocked position and for shifting said coupler laterally, said means involving a lever comprising relatively movable connected sections, one of said sections being independently movable to effect an unlocking movement of said coupler locking mechanism.

2. In mechanism of the character indicated, the combination with a laterally movable car coupler, of means for moving the locking mechanism of said coupler to unlocked position and for shifting said coupler laterally, said means involving a lever comprising a plurality of pivotally connected sections, said sections being conjointly movable to effect a lateral shifting of the coupler locking mechanism.

pler, and one of said sections being independently movable to effect an unlocking movement of said coupler locking mechanism.

3. In mechanism of the character indicated, the combination with a laterally movable car coupler, of means for moving the locking mechanism of said coupler to unlocked position and for shifting said coupler laterally, said means involving a jointed lever which is attached at one end to the railway vehicle.

4. In mechanism of the character indicated, the combination with a laterally movable car coupler, of means for moving the locking mechanism of said coupler to unlocked position and for shifting said coupler laterally, said means involving a lever comprised of two pivotally connected sections, one of said sections being rotatable with respect to the other to effect an unlocking movement of said coupler locking mechanism, and said lever being rotatably secured at one end to the railway vehicle.

5. In mechanism of the character indicated, the combination with a laterally movable car coupler, of means for shifting said coupler laterally, said means involving a lever having a ball and socket connection with the railway vehicle, the socket having oppositely disposed downwardly flaring recesses.

6. In mechanism of the character indicated, the combination with a laterally movable car coupler, of means for moving the locking mechanism of said coupler to unlocked position and for shifting said coupler laterally, said means involving a lever having a ball and socket connection with the railway vehicle, and means operatively connecting said lever to said locking mechanism,

said lever being comprised of a plurality of 40 pivotally connected sections.

7. In mechanism of the character indicated, the combination with a laterally movable car coupler and its knuckle and locking mechanism, of a jointed lever rotatably connected to the railway vehicle, and a rotatable rod operatively connecting said lever and locking mechanism and adapted to move said locking mechanism to unlocked position and to shift said coupler laterally, said rotatable 50 rod being connected to one of the sections of said jointed lever.

8. In mechanism of the character indicated, the combination with a laterally movable car coupler, of means for shifting said 55 coupler laterally, said means involving a lever movably connected to the railway vehicle, and means operatively connecting said lever and coupler, said lever being provided with a projection, and the railway vehicle 60 having mounted thereon means for supporting said lever, said supporting means comprising separable members constituting a socket for receiving the projection on said lever.

9. In mechanism of the character indicated, the combination with a laterally movable car coupler, of means for shifting said 70 coupler laterally, said means involving a lever having a plurality of pivotally connected members and having a connection with the railway vehicle which prevents substantial rotations of said lever except about two axes extending at an angle to each other, one of said axes extending in the direction of 75 length of said lever.

In testimony whereof I affix my signature.
WM. A. REDMAN.
